UNITED STATES PATENT OFFICE

PAUL P. CARBT, OF CHICAGO, ILLINOIS

RADIATOR METER

Application filed February 16, 1927. Serial No. 168,713.

This invention relates to improvements in radiator meters for automobiles and its object is to provide a simple, efficient device of this type that is cheap to manufacture. With the foregoing and other objects in view the invention consists in the combination and arrangement of parts to be hereinafter fully described, particularly pointed out in the appended claim and illustrated in the accompanying drawings which form a part of this application and in which—

Fig. 1 is a fragmentary view of an automobile illustrating the application of the radiator meter.

Fig. 2 is an enlarged fragmentary sectional view of the radiator meter.

Fig. 3 is a sectional view of the water box and float employed.

Fig. 4 is a detail of the rod and split pipe connection employed.

Fig. 5 is a face view of the indicator.

Like reference characters denote corresponding parts throughout the several views.

It is important in water cooled motors that a sufficiency of the cooling liquid be constantly maintained in the circulating system. In the winter season when anti-freeze mixtures are added they often evaporate and the amount of cooling liquid necessary is reduced with possible ill effects to the motor. It is entirely possible that at any time of the year a leak may drain some or all of the cooling liquid, evaporation may reduce it and, without the driver's knowledge, the cooling liquid may be insufficiently provided.

It is the purpose of the present invention to avoid this condition and to this end an indicator installed upon the instrument board will at all times denote the amount of water, or the level thereof, in the radiator.

The reference numeral 1 denotes an automobile provided with the radiator 2 and hood 3. To the partition 4 beneath the hood I secure a water box 5 which is provided with the supply pipe 6 having the control valve 7, said pipe 6 leading through the said partition 4 and thereafter being coiled, as at 8, and extending into the water circulation system so that the water passing from the radiator through the entire circulation system is also

admitted, when the valve 7 is open, to the water box.

The top of the water box is substantially on a level with the top of the radiator and when the water pump is not in operation the level of the water in the water box is the same as that in the radiator. Within the water box is a float 9 that is adjustably disposed upon an angular rod 10 that at its upper end is threaded, nuts 12 upon said rod serving to securely retain the float in any adjusted position upon the rod. The rod 10 extends out through one side of the water box, through the gland 13 and into a sleeve 14 and terminates within a pipe 15 also disposed within said sleeve wherein said pipe 15 is free to rotate, the rod 10 and pipe 15 being connected together by the pin 16, said pipe 15 at one end being formed with the slot 17 to receive the pin 18 of a rod 19 that extends into the housing 20 imbedded in the dash 21 and through a dial 22 within said housing and at its end carries the indicator 23 that works over the graduations, in fractions of an inch, on the face of the dial, said indicator being visible through the lens 24 of the casing 20.

One end of a tubular support 25 for the sleeve 14 is secured to the casing 20. The depth of the water box is known in inches or fractions thereof and also the depth of the water in that box when the radiator is full. The full position of the radiator may be denoted on the dial by the graduation 8. A dangerous low water point in the radiator may be denoted by the graduation 0 on the dial and intermediate water levels may be denoted by the intermediate graduations, the water level being readable by means of the indicator's position upon the dial. If the high water level in the radiator should cause, through the medium of the float in the water box, an indicator reading that would tend to go beyond the graduation 8 the float may be adjusted upon its rod 10 until the full radiator position would cause the indicator to read upon graduation 8 of the dial.

The water box is provided with an air vent 26 provided with a hinged closure 27 that rests upon the float and should the water in

the radiator run over or boil over the water box would be prevented from doing likewise by the action of the float which would rise until it closed the member 27 against said vent.

- 5 Vibration due to operation of the automobile will not effect the meter or break or strain any of its parts as the connections between the float and indicator are to a certain extent flexible. The pipe 15 and rod 19 are capable 10 of relative longitudinal movement without separation and the coiled portion 8 of the pipe 6 contributes a certain flexibility.

What is claimed is:—

- 15 The combination with the water circulating system of an automobile, said system including a radiator, of a water box having its top substantially level with that of the radiator and provided with an air vent, a flexible 20 water conduit leading from said water box into the water circulation system, a float in said water box, a hinged closure for the air vent in said water box and operatively supported by said float, a graduated dial arranged in the dash of the automobile, an indicator movable over the face of said dial, and actuating means for said indicator connecting it to said float, said means comprising 25 a rod bent between its ends so as to provide two arms at an angle to one another, one arm 30 adjustably receiving the float and a rotary pipe pin-connected to the other arm and actuated thereby.

In testimony that I claim the foregoing 35 as my own I have hereto affixed my signature.

F. P. CARBT.
